FIG. 1.

FIG. 2.

FIG. 3.

Invention:

Henry Tscherring,
By Dyersforth, Lee, Clinton & Miles,
Attys.

UNITED STATES PATENT OFFICE.

HENRY TSCHERNING, OF FREEPORT, ILLINOIS, ASSIGNOR TO ARCADE MANUFACTURING COMPANY, OF FREEPORT, ILLINOIS, A CORPORATION OF ILLINOIS.

MOP.

Application filed August 21, 1922. Serial No. 583,261.

To all whom it may concern:

Be it known that I, HENRY TSCHERNING, a citizen of the United States, residing at Freeport, in the county of Stephenson and 5 State of Illinois, have invented a new and useful Improvement in Mops, of which the following is a specification.

My invention relates, more particularly, to mops of the type comprising a handle 10 portion carrying at one end a head connected therewith and forming a stationary jaw and involving a bail-like movable jaw cooperating with the stationary jaw and between which the swab is relatively held, the movable jaw cooperating with a spring which surrounds the handle and is engaged by a device which when moved to one position opens the jaws and when actuated to another position forces the movable jaw toward the fixed jaw, by a yielding action whereby the jaws accommodate themselves to swabs of different thicknesses and firmly 20 clamp the same therebetween.

The springs referred to, as mops of the 25 general character above stated have hitherto been provided are of the coil type, it being the intention, in the manufacture of the mops, to hold the outer end of the coil spring in fixed relation to the head forming the stationary jaw, the opposite free end of the spring being engaged by the device through the medium of which the bail-like movable jaw is actuated to different positions relative 30 to the stationary jaw as stated. As these devices have hitherto been provided the coil 35 spring would oftentimes rotate on the handle portion out of engagement with the fastening means at its outer end and would result in the detrimental disarrangement of the 40 parts of the construction.

My object is to provide a novel, simple and economical construction of mop in which provision is made for preventing the rotation of the coil spring into a position where- 45 in disarrangement of the parts affecting the functioning of the device results.

Referring to the accompanying drawing:

Figure 1 is a view in front elevation of a 50 mop constructed in accordance with my invention, a portion of the handle being cut away and the swab omitted. Figure 2 is an edge view of the construction shown in Fig. 1; and Figure 3, a section taken at the line

3—3 on Fig. 1 and viewed in the direction of 55 the arrows.

In the construction shown the handle portion of the mop represented at 4, and which is commonly made of wood, is provided at its outer end with a head 5 shown as formed of sheet metal and of common construction, this head comprising the stationary one of the swab-holding jaws of the device. The head 5 is held on the handle 4 by means of a staple 6 which passes at one of its prongs 60 through an opening 7 in the head 5 and extends at both of its prongs into the handle portion 4. The movable bail-like jaw of the mop is represented at 8 and cooperates with the stationary jaw as in constructions as 65 hitherto provided, the rear arms of the bail, these arms being represented at 9, being connected with a plate-like member 10 which opposes a side of the handle 4, is transversely curved and presents rearward extending ears 70 75 11 to which the arms 9 are connected, the upper end of the plate-like member 10 being formed with a loop 12. The construction also involves a coil spring 13 which surrounds the handle portion 4 and is com- 80 pressible in a direction lengthwise of the latter. The upper end of the spring 13 abuts the under side of the head 5 and is held in position by means of the staple 6 through which the free upper end 14 of the spring 85 extends. The lower end of the spring 13 passes loosely through the loop 12 of the plate 10.

The operation of the construction to clamp 90 a swab between the jaws thereof is the same as that of structures now commonly in use.

The free end 14 of the spring beyond the staple 6 is shown as outwardly deflected as represented at 15, the purpose of this deflection being to prevent the rotation of the 95 spring 13 out of engagement with the staple 6, whereby the parts of the structure are prevented from becoming disarranged and impairing the functioning of the device, it being noted that, in the particular construction shown a single fastening device in the form of a relatively inexpensive staple is provided for serving the double function of holding the spring against rotation and holding the stationary jaw-forming head in 100 105 place on the handle portion 4.

While I have illustrated and described a particular construction embodying my in-

vention, I do not wish to be understood as intending to limit it thereto as the same may be variously modified and altered without departing from the spirit of my invention. 5. What I claim as new, and desire to secure by Letters Patent is:

A mop comprising, in combination, a bar, a jaw on said bar, a second jaw movable relative to said first-referred to jaw, a coil spring 10 surrounding said bar and compressible

lengthwise thereof to force said movable jaw 15 toward said first-named jaw to clamp and retain a swab therebetween, one of the convolutions of said spring having a deflected portion, and a staple embracing said convolution and co-operating with the deflected 20 portion thereof whereby to prevent the spring from turning.

HENRY TSCHERNING.
